UNITED STATES PATENT OFFICE

121,410

DESIGN FOR A RIDGE VENTILATOR

Edward R. Gunter, Dubuque, Iowa

Application January 26, 1940, Serial No. 89,739

Term of patent 14 years

To all whom it may concern:

Be it known that I, Edward R. Gunter, a citizen of the United States, residing at Dubuque, in the county of Dubuque and State of Iowa, have invented a new, original, and ornamental Design for a Ridge Ventilator, of which the following is a specification, reference being made to the accompanying drawing, forming a part thereof.

Fig. 1 is a side elevational view of a ridge ventilator embodying my new design;

Fig. 2 is a top plan view thereof and

Fig. 3 is a perspective view thereof.

I claim:

The ornamental design for a ridge ventilator, substantially as shown.

EDWARD R. GUNTER.
